DOOR CHIME

Norman William Stevenson, Macclesfield, England, assignor to V. & E. Friedland Limited, Macclesfield, England, a British company

Filed Dec. 4, 1961, Ser. No. 67,779

Claims priority, application Great Britain June 2, 1961

Term of patent 14 years

(Cl. D72—1)

FIG. 1 is a perspective view of a door chime showing my new design;

FIG. 2 is a rear perspective view thereof;

FIG. 3 is a top plan view thereof; and

FIG. 4 is a front elevation thereof.

My design for a door chime is characterized by the narrow groove between the sides of the central rectangular member and the outer U-shaped member in association with the circumferential groove surrounding the circular center element of the central rectangular member all as shown.

I claim:

The ornamental design for a door chime, as shown and described.
